US00D884915S

(12) **United States Design Patent** (10) **Patent No.:** **US D884,915 S**
Wersland et al. (45) **Date of Patent:** **** May 19, 2020**

(54) **PERCUSSIVE MASSAGE DEVICE**

(71) Applicant: **Theragun, LLC**, Beverly Hills, CA (US)

(72) Inventors: **Jason Wersland**, Manhattan Beach, CA (US); **Benjamin Nazarian**, Beverly Hills, CA (US); **Jaime Sanchez Solana**, Los Angeles, CA (US); **Eduardo Merino**, Beverly Hills, CA (US); **Trent Hernandez**, Los Angeles, CA (US)

(73) Assignee: **THERAGUN, INC.**, Beverly Hills, CA (US)

(**) Term: **15 Years**

(21) Appl. No.: **29/708,809**

(22) Filed: **Oct. 9, 2019**

Related U.S. Application Data

(63) Continuation-in-part of application No. 29/674,846, filed on Dec. 26, 2018, now Pat. No. Des. 880,716.

CLAIM

The ornamental design for a percussive massage device, as shown and described.

DESCRIPTION

FIG. 1 is a top perspective view of a percussive massage device, showing our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a bottom perspective view thereof.
